UNITED STATES PATENT OFFICE

147,651

DESIGN FOR A JEWELRY DISPLAY BOX

Abbot A. Harman, New York, N. Y.

Application April 29, 1946, Serial No. 129,075

Term of patent 3½ years

(Cl. D80—5)

To all whom it may concern:

Be it known that I, Abbot A. Harman, a citizen of the United States of America, residing at New York city, in the county of New York and State of New York, have invented a new, original, and ornamental Design for a Jewelry Display Box, of which the following is a specification, reference being had to the accompanying drawing, forming a part thereof.

In the drawing:

Figure 1 is a perspective view of a jewelry display box showing my new design.

Figure 2 is an end elevational view of the same.

I claim:

The ornamental design for a jewelry display box, as shown.

ABBOT A. HARMAN.
